PRESSURIZED CONTAINER VALVE

John E. Ayres, Elizabeth, N. J., assignor, by mesne assignments, to Oil Equipment Laboratories, Incorporated, Elizabeth, N. J., a corporation of New Jersey

Application June 24, 1950, Serial No. 170,163

11 Claims. (Cl. 222—394)

1

Various products in more or less liquid form, such as whipped cream, brushless shaving cream and so forth, are marketed in what are termed pressurized containers; that is, valve-equipped receptacles containing the product and charged with a gaseous medium held under pressure and serving as a propellant for discharging or dispensing the product upon actuation of the container valve. Since it is not feasible for the purchaser to refill such containers when empty, they fall in the "throw-away" category.

The present invention relates to the valves of such pressurized containers and has for its primary object to provide a valve structure which is convenient to manipulate, provides effective control of the discharge of the product and also against leakage, and which, at the same time, is susceptible to manufacture at low cost.

Other objects and advantages of the invention will be apparent from the following description of the forms shown in the accompanying drawings, in which:

Fig. 1 is a vertical section of a pressurized container equipped with one form of dispenser valve according to the invention;

Fig. 2 is an enlarged vertical section of the valve of Fig. 1 and the container cap before application to the container;

Fig. 3 is a vertical section of the upper portion of a container incorporating a modified form of valve;

Fig. 4 is a view similar to Fig. 2 but showing a further modification; and

Fig. 5 is a horizontal section on the line V—V of Fig. 1.

Referring first to the valve construction of Figs. 1 and 2, a container 1 is shown provided with a closure cap 2. This particular container cap, which, per se, forms no part of the invention, is formed up as shown in Fig. 2 and then is applied to the container, to seal it, as shown in Fig. 1, with the cap flange 3 crimped around the bead 4 which surrounds the mouth of the container.

According to this application of the present invention, the dispenser valve, generally, designated 5 in Fig. 1, is carried by the container cap, to which it may be pre-assembled as a unit.

The valve comprises a body 6 of tubular form, which may be produced cheaply on an automatic eyelet machine, the tube being centered in an opening in the cap and protruding above and below it. The body is secured to the cap as by soldering, as indicated at 7. The lower end of the valve body has an integral valve seat,

2

which can be made by simply forming up the lower end portion of the body tube to provide an upwardly and inwardly extending flange 8.

A valve plunger is located in the center opening of the valve seat, with a head 9 depending below the seat and a stem 10 extending up through and protruding above the upper end of the valve body. A sealing ring 11 of rubber or the like encircles and grips the lower end of the plunger adjacent its head 9 and the plunger is urged upwardly and the sealing ring held in engagement with the valve body seat by a spring 12. The lower end of the spring seats in the space between the valve seat flange and the wall 15 of the valve body; and the upper end of the spring is suitably engaged with the plunger stem, as by the projections 13 struck up from the stem.

As presently referred to in greater detail, the valve is opened by depressing the plunger; and 20 in order to guard against the sealing ring 11 adhering to the valve seat, the ring is suitably locked to the plunger. This may be achieved by forming small flanges 14 on the plunger adjacent the head 9 to afford the sealing ring a 25 better grip on the plunger and ensure its moving with the plunger when the latter is depressed.

The upper end of the plunger 10 is shown threaded, at 15, to receive a locking nut 16 which, when turned down against the upper end 30 of the valve body 6, serves to hold the valve closed and prevent inadvertent discharge of the product as the result of pressure accidentally applied to the top of the plunger.

35 A syphon tube 17 depends from the dispenser valve to the bottom of the container, the tube preferably being flexible and attached to the valve body simply by its snug fit. Tubes of polyethylene are found to be suitable for the purpose.

40 The outer end of the valve body carries a suitable discharge spout preferably of molded plastic material. Polyethylene is also suitable for this purpose. In the form shown, the spout consists of a hollow hub portion 18 surrounded by a flange 45 19 to rest on the cap flange and form a neat closure for the latter. The spout proper or nozzle 20 is in communication through the port 21 with the interior of the hub portion. This discharge spout is arranged to lie in the same vertical plane as the syphon tube to facilitate complete emptying of the container.

50 This relationship is maintained by forming a flat 22 at the upper end of the valve body and molding the spout with a complementary shoulder 23 to prevent the spout from turning on the valve body.

As will be understood, the syphon tube is applied and inserted in the container in conformity with this setting of the spout.

The spout is a snug push-fit on the valve body but is removable to give access to the lock nut 16. However, after the lock nut has been backed off one or two turns, or enough to permit the required depression of the plunger to open the valve, it is unnecessary to remove the spout each time the valve is to be opened because the plunger can be depressed by applying finger pressure to the thin walled section 24 of the spout which bears against the top of the plunger, as shown in Fig. 1. If the spout is made of sufficiently elastic material, such as polyethylene, it can be rotated to turn the nut 16, making it unnecessary to remove the spout as above suggested. The correct positioning of the spout in relation to the syphon tube is then determined by the snap-engagement of the shoulder 23 and flat 22.

In dispensing products from pressurized containers, the extent to which the valve is opened requires careful control in order to avoid too rapid and, hence, excessive discharge of the products; and the present invention provides for such control while avoiding the expense incident to the maintenance of unduly close tolerances in the manufacture of the parts.

As shown in Fig. 2, the major part of the length of the plunger immediately below the threaded section 15, is cylindrical, whereas the lower section 25 is enlarged and slightly tapered, the two sections merging at the shoulder 26. By slightly tapered is meant a taper of the order of .004"-.010" in a length of some .187".

In forming up the valve seat flange 8 the central opening is deliberately undersized, instead of any effort being made to hold it to a close finished size. The tapered section of the valve plunger, on the other hand, is dimensioned (again without the necessity of holding it to extremely close tolerances) to be an actual force fit in the valve opening. When the valve is assembled, the plunger is forced up through the under-sized flange opening and actually enlarges it to its final size, the rubber ring 11 being engaged with the valve seat and the spring 12 applied and anchored at its upper end while the parts are in this position. During this operation the rubber ring is held under greater compression than that created by the spring and the pressure within the container, so that when the pressure so applied at assembly is removed, the plunger drops back slightly, leaving the rubber ring closely engaged with the valve seat but with a slight clearance around the plunger at the central opening in the seat. Thus, when the parts are assembled, the valve opening is effectively closed; and when the plunger is depressed, the slight taper on the section 25 provides a closely controlled, small opening appropriate for the discharge of the product, the full extent of the opening being limited by the backed-off position of the lock nut 16. By making the tapered section of the plunger a force fit in the valve flange, the escape passage for the product when the plunger is depressed is more closely controllable than would be the case if the plunger and valve seat opening were both attempted to be pre-sized with normal production tolerances.

The described construction also facilitates filling of the container by the so-called direct filling method. As will be recognized, an actuating rod or the like forming part of the filling mechanism can be applied to depress the plunger to an

extent sufficient to bring the reduced diameter upper section of the plunger into the valve flange opening and thereby provide an enlarged filling passage.

In the form shown in Fig. 3, the many components corresponding to those above mentioned are correspondingly numbered with primed characters and need no further description.

In this instance the rubber ring 11' is further locked to the plunger by means of a cup 30 which is crimped against the rubber to pinch the ring into close engagement with the plunger stem.

Also, the locking unit 31, which corresponds in function to the locking unit 16, is mounted on the outside instead of the inside of the spout unit, the threaded section 15' of the upper end of plunger 10' projecting up through an aperture 32 in the top wall of the spout. To guard against leakage of the product through this aperture when the locking unit is backed off the turn or two necessary to free the plunger, a seal is provided in the form of an upstanding continuous flange 33 molded as an integral part of the spout unit and telescoped with a recess 34 in the nut.

In the form of the invention shown in Fig. 4, the plunger 35 is formed with a head section 36 at its lower end, which section is provided with a series of grooves 37. A sealing ring 38 engages a formed up valve seat, as before, but the center opening in the valve seat is dimensioned to provide clearance around the plunger 35 at all times. It has been found that the sealing ring, in this construction, will adhere to the valve seat when the plunger is depressed, so that the outlet passage for the product is represented by the gap which opens up between the lower end of the sealing ring and the plunger head 39, the product then passing up through the grooves 37 and through the valve body to a spout, as before. During filling, when this modified construction is used, the pressure of the entering products serves to force the rubber ring off the seat so that, as in the previous forms, a larger filling opening is provided.

It will be recognized that the foregoing constructions are illustrative only and that the invention may be embodied in various equivalent forms. In the light of the description of these illustrative embodiments, the following is claimed:

1. A dispenser valve mechanism for a pressurized container having a closure cap comprising a tubular valve body of sheet material having imperforate side walls and being open at its ends, said valve body extending through the cap and being secured to the cap intermediate its ends with its lower end protruding below and its upper end protruding above the cap, a valve seat having an aperture therein carried by the lower end of the valve body, a valve operating plunger extending through the aperture in the valve seat, said plunger having an actuating stem extending through the valve body and projecting beyond the upper end thereof and a headed end projecting beneath the valve seat at the lower end of the valve body, said actuating stem being spaced from the side walls of the valve body, said plunger also having a gradually tapered section adjacent and sloping outwardly toward the headed end thereof, said tapered section fitting within the aperture in the valve seat and engaging with the edges of the valve seat defining the aperture therein at a point intermediate the ends of said tapered section, sealing means secured to the lower end of the plunger and a spring engaging

5.

with the plunger and urging the plunger upwardly in the valve body to engage the sealing means on the plunger with the valve seat and the tapered section of the plunger with the edges of the valve seat defining the aperture therein.

2. A dispenser valve mechanism for a pressurized container having a closure cap as defined in claim 1 wherein the valve seat carried by the lower end of the valve body comprises a substantially conical flange extending inwardly and upwardly from the lower end of the valve body with the inner edges thereof defining the aperture in the valve seat and the tapered section of the plunger makes a force fit with the inner edges of the flange at a point intermediate the ends of said tapered section.

3. A dispenser valve mechanism for a pressurized container having a closure cap as defined in claim 1 wherein the operating stem of the valve plunger is of a smaller diameter than the aperture in the valve seat.

4. A dispenser valve mechanism for a pressurized container having a closure cap as defined in claim 1 which includes a retaining cup carried by the plunger at the headed end thereof, said retaining cup surrounding a portion of the sealing means and holding the sealing means in place on the plunger.

5. In a dispenser valve mechanism, the combination of a valve body of sheet material having tubular side walls, said body being open at one end and having an apertured valve seat formed at the other end thereof, said valve seat comprising a substantially conical flange extending inwardly from the valve body with the inner edges of said flange defining the aperture in the valve seat, a valve plunger extending through the aperture in the valve seat, said plunger having an operating stem at one end thereof projecting beyond the valve body with the other end of the plunger projecting beneath the valve seat, said operating stem being of a smaller diameter than the aperture in the valve seat, said plunger also having a tapered section adjacent and sloping outwardly toward the end of the plunger projecting beneath the valve seat, said tapered section sloping gradually from a diameter smaller than the diameter of the aperture in the valve seat to a diameter larger than said aperture, and engaging with the edges of the flange defining said aperture at a point intermediate the ends of said section, sealing means secured to the end of the plunger beneath the valve seat and spring means engaging with the plunger, said spring means being biased to urge the plunger in a direction to hold the sealing means in engagement with the valve seat and the tapered section of the plunger in engagement with the edges of the flange defining the aperture in the valve seat.

6. A dispenser unit for a pressurized container comprising the combination of a closure cap having an opening therein, a tubular valve body of sheet material having imperforate side walls and being open at its ends, said valve body extending through the opening in the cap and being sealed to the cap at a point intermediate the ends of the valve body with its lower end protruding below and its upper end protruding above the cap, a valve seat having an aperture therein carried by the lower end of the valve body, a valve operating plunger extending through the aperture in the valve seat, said plunger having an actuating stem projecting beyond the upper end of the valve body and a headed end projecting beyond the valve seat at the lower end of the

6.

valve body, said operating stem being of a smaller diameter than the opening in the upper end of the valve body and being spaced from the side walls of the valve body, said plunger also having a gradually tapered section adjacent and sloping outwardly toward the headed end thereof, said tapered section fitting within the aperture in the valve seat and engaging with the edges of the valve seat defining the aperture therein at

5 10 a point intermediate the ends of said tapered section, sealing means secured to the lower end of the plunger and a spring surrounding the plunger within the valve body, one end of said spring engaging with the plunger and the other end of the spring engaging with the rear of the valve seat, said spring being biased to urge the plunger upwardly in the valve body to engage the sealing means on the plunger with the valve seat and the tapered section of the plunger with 15 the edges of the valve seat defining the aperture therein.

7. In a dispenser unit for a pressurized container having a closure cap, the combination comprising, a tubular valve body of sheet material having imperforate side walls and being open at its ends, said valve body extending through the cap and being secured to the cap intermediate its ends with its lower end protruding below and its upper end protruding above the cap, a valve seat

20 25 30 having an aperture therein carried by the lower end of the valve body, a valve operating plunger extending through the aperture in the valve seat, said plunger having an actuating stem extending through the valve body and a headed end projecting beneath the valve seat at the lower end of the valve body, said stem having a threaded end projecting beyond the upper end of the valve body and being of a smaller diameter than the aperture in the valve seat and the opening in the upper end of the valve body, said plunger also

35 40 45 having a gradually tapered section adjacent and sloping outwardly toward the headed end thereof, said tapered section fitting within the aperture in the valve seat and engaging with the edges of the valve seat defining the aperture therein at a point intermediate the ends of said tapered section, sealing means secured to the lower end of the plunger, a spring engaging with the plunger and urging the plunger upwardly in the valve body

50 55 60 to engage the sealing means on the plunger with the valve seat and with the tapered section of the plunger with the edges of the valve seat defining the aperture therein, a locking nut engaging with the threaded end of the operating stem projecting beyond the upper end of the valve body for controlling operation of the plunger independently of the spring and a dispenser spout telescopically fitted over the upper end of the valve body, said spout having a passageway communicating with the opening in the upper end of the valve body and a discharge outlet communicating with said passageway.

8. In a dispenser unit for a pressurized container having a closure cap, the combination as defined in claim 7 wherein the threaded end of the operating stem projects beyond the dispenser spout and the locking nut engages with the dispenser spout to hold the valve in closed position.

9. In a dispenser unit for a pressurized container, the combination as defined in claim 7 wherein the threaded end of the operating stem projects beyond the dispenser spout and the dispenser spout carries a sealing flange and the locking nut contains a recess engaging with the sealing flange on the dispenser spout.

10. In a dispenser valve mechanism for a pressurized container, the combination comprising a valve body of sheet material having tubular side walls and being open at its ends, a flange extending inwardly from said body at one end thereof and formed integrally therewith, said flange forming a valve seat and defining the opening at said end of the valve body, a valve plunger extending through the opening defined by the flange with its lower end projecting beneath said flange, said plunger having an operating stem projecting beyond the valve body and a slightly tapered section intermediate its ends, said operating stem being of a smaller diameter than the internal diameter of the valve body and the opening therein, said tapered section of the plunger sloping outwardly toward the lower end of the plunger to a diameter larger than the diameter of the opening defined by the flange and making a force fit with said flange at a point intermediate its ends and sealing means of compressible material carried by the plunger and engaging with the valve seat.

11. In a dispenser valve mechanism for a pressurized container, the combination comprising a valve body of sheet material having tubular side walls and being open at its ends, a flange extending inwardly from said body at one end thereof and formed integrally therewith, said flange forming a valve seat and defining the opening at said end of the valve body, a valve plunger extending through the opening defined by the flange with its lower end projecting beneath said

5
10
15

flange, said plunger having an operating stem projecting beyond the valve body and a slightly tapered section intermediate its ends, said operating stem being of a smaller diameter than the internal diameter of the valve body and the opening therein, said tapered section of the plunger sloping outwardly toward the lower end of the plunger to a diameter larger than the diameter of the opening defined by the flange and making a force fit with said flange at a point intermediate its ends sealing means of compressible material carried by the plunger and engaging with the valve seat and a retaining cup carried by the plunger, said cup surrounding a portion of the sealing means and holding the sealing means in place on the plunger.
